UNITED STATES PATENT OFFICE.

LEONARD E. ASKE, OF DULUTH, MINNESOTA.

ELECTRIC HEATER OR VAPORIZER.

Application filed September 11, 1925. Serial No. 55,761.

My invention relates to electric heaters and vaporizers and has for its object the provision of an improved heater suitable for use to convert cold hydrocarbon fuel into hot fumes in the intake manifold of an internal explosion engine preparatory to starting the engine. With this and other objects in view, it consists of the structures, combinations and arrangements of parts hereinafter described and claimed.

In the accompanying drawing, Fig. 1, is a vertical section of my invention on the line A—B of Fig. 4, omitting the hereinafter described absorbing pads or sponges. Fig. 15 2, is a vertical section, partly in elevation, approximately on the line E—F of Fig. 4, omitting said pads and omitting the herein-after described sleeve or tube 10 and screen 11. Fig. 3, is a vertical section on the line 20 C—D of said Fig. 4, including said pads and tube and screen. Fig. 4, is a top plan view of said invention. Fig. 5, is a bottom plan view of said screen. Fig. 6, is a perspective view of a group of three absorbing pads 25 or sponges forming part of said invention. Fig. 7, is a side elevation partly broken away of a carbureter and intake manifold, showing my heater in operating position therein. Fig. 8, is a side elevation of said 30 tube partly broken away. Fig. 9, is a side elevation of my said invention.

In said drawings, 1 is a hollow plug of any suitable structure, preferably comprising a head portion and a reduced externally 35 threaded body portion, containing a chamber 1^a. Extending axially through said head portion into said chamber is a metal binding post 2 which is electrically insulated from said plug in any suitable manner or by 40 any suitable means, as by a thimble 3, and washers 3^a, 3^b, and 3^c of insulating material.

Electrically connected at one end to said post in any suitable manner, as by riveting said end in a recess in the head of said post 45 as at 2^a is an electric resistance wire 4 which is preferably bent into one or more vertical loops, as 4^a, 4^b, and 4^c, the opposite end of which looped wire is electrically grounded in any suitable manner or by any suitable 50 means, as by being riveted in a recess in said head portion as at 1^b, said wires constituting an electric heating element. Mounted on said post are clamping nuts 2^b and 2^c for connecting an electric circuit wire 5, thereto. 55 A parallel resistance wire 6, looped in similar manner to the first and spaced there-

from, is preferably secured in like manner to said post and plug head. Inserted between said parallel resistance wires is a refractory absorbent pad or sponge 7 made 60 of any suitable material, for example of asbestos fibre wool, and similar pads 8 and 9 are positioned against the opposite sides of said wires; so that said parallel wires are each positioned between absorbent side 65 walls. If only one resistance wire is used the number of said walls may be reduced to two, of such thickness as may be desirable.

A tube or sleeve 10 of any suitable material, as brass, adapted to surround said pads 70 and to hold them in position and press them against said resistance wires, is thrust at one end into the chamber 1^a of said plug and is secured therein in any suitable manner, as by frictional contact therewith, or 75 by cementing it with shellac to the inner side wall of said plug. The free end of said tube is preferably provided with an inwardly directed flange 10^a to support a screen 11 positioned therein; said screen being 80 adapted to prevent any of said pads or materials thereof from falling into the stream of fuel passing from the carbureter to the engine. Said tube has formed therein near its free end a drainage port 10^b, adapted to 85 prevent the flooding of the adjacent ends of said pads and adjacent bends of the heating elements by liquid fuel. An intake port 10^c is formed in said tube outward of said plug but adjacent thereto for receiving fluid to 90 be heated or fumed, and transversely extending apertures X, Y, are preferably formed through said pads and adapted to communicate with the ports 10^b and 10^c, respectively, 95 to facilitate the flow of the fuel or fumes into and out of the spaces between said pads.

The end faces of the outer bends of said heating elements are preferably exposed 100 at the outer ends of said pads, the ends of the pads not being drawn together over them.

G, is a gasket of any suitable material, preferably of metal, as copper.

In operation said heater is extended into 105 a chamber 12^a in a housing 12 preferably on the air intake tube 13 of a carbureter 14, from the side walls of which chamber said heater is preferably spaced. The free end of the tube and the adjacent ends of the 110 pads and heating elements project upwardly very slightly above the floor of said intake

- tube, so that said ends will not be flooded if said chamber 12^a fills with liquid fuel. It will be understood, however, that if desired said plug may be directed downwardly from the top of a carbureter throat or other suitable position, which may be found advisable in connection with some forms of carbureters, or intake manifolds, or other conductors of fluid to be heated or fumed. Said heater 10 may be primed by removing it temporarily and dipping it in gasoline, but in general practice the engine will first be turned over by cranking, or by means of an electric starting motor, as is well known to the art, 15 a damper or valve 15 in said air intake tube being partly closed. A partial vacuum will be created in the air intake end of said tube and a spray of heavy gasoline or fuel oil will be drawn from said carbureter a short 20 distance into the manifold 14^a but will fall back by gravity, and a portion of it will drop into said chamber 12^a, or will drop onto the floor of said tube 13 and flow into said chamber 12^a and thence through the port 25 10^a and be absorbed by said pads. An electric circuit of any suitable structure including said heating elements then being closed, the fuel in said pads will be heated and fumized and will follow the loops of said 30 wires to their outward bends and escape through said screen into the air intake tube and manifold, mixing with the incoming air. This light, hot mixture will then be drawn into the engine cylinders for starting purposes.
- It is obvious that my said invention may be modified in various particulars within the spirit and scope of certain of my claims.
- What I claim is:
1. The combination of a case comprising a 40 plug member and a tube member, an electric binding post extending through a wall of one of said members and insulated therefrom, an electric heating wire electrically connected at one end to said post, and electrically connected at its opposite end to one of said members, and absorbent means in contact with said wire.
2. The combination of a plug, an electric 45 binding post extending through said plug and insulated therefrom, an electric heating
- wire electrically connected to said post and to ground, refractory absorbent means positioned against one side of said wire, and adapted to form one side wall for the major 55 part thereof, a tube extending from said plug and surrounding said absorbent means and the major portion of said wire, said tube having an intake port formed therein near its engaged end, and a drainage port 60 formed therein near its free end.
3. The combination of a plug, an electric binding post extending through said plug and insulated therefrom, an electric heating wire electrically connected to said post and to ground, refractory absorbent means positioned against two sides of said wire and adapted to form opposite side walls for the major part thereof, and a tube extending from said plug and surrounding said 70 absorbent means.
4. The combination of a case comprising a 75 plug member and a tube member, an electric binding post extending through said plug and insulated therefrom, an electric heating wire extending into said tube and electrically connected at one end to said post and at its opposite end to ground, absorbent means in contact with said wire within said tube, a screen extending across 80 the free end of said tube and supported thereby, said tube having a drainage port formed in its side near its free end, said tube having an intake port formed in its 85 side.
5. The combination of a plug, an electric binding post extending through said plug and insulated therefrom, an electric heating wire electrically connected to said post and to ground, refractory absorbent pads positioned against two sides of said wire and adapted to form opposite side walls for the major part thereof, a tube extending from said plug and surrounding said absorbent pads, the wall of said tube having a port 90 extending therethrough, one of said pads having a port extending therethrough adapted to communicate with the port in said tube wall.
- In testimony whereof, I hereunto affix my 100 signature.

LEONARD E. ASKE.
